UNITED STATES PATENT OFFICE

LOUIS BEEG, OF FLINT, MICHIGAN, ASSIGNOR TO A C SPARK PLUG COMPANY, OF FLINT, MICHIGAN, A COMPANY OF MICHIGAN

HAIR-SPRING-SECURING MEANS FOR INSTRUMENTS

Application filed September 17, 1928. Serial No. 306,424.

This invention relates to measuring instruments and more particularly to the securing means for the hair spring functioning to restore the indicating means of such instruments to the zero position.

An object of the invention is to provide an improved securing means for the hair spring to obtain greater uniformity and efficiency.

As another object, the securing means is such as to avoid twisting or deformation of the spring at its point of attachment.

Another object of the invention is to provide a securing means for the hair spring whereby the hair spring at its end is held concentrically in all positions of adjustment.

Other objects and advantages will be understood from the following specification.

The invention is illustrated in the accompanying drawing, in which:

20 Figure 1 is an enlarged vertical central sectional view of a tachometer showing the hair spring friction adjuster applied;

Figure 2 is a vertical front elevation of the tachometer with the dial removed to show the 25 adjuster in place;

Figure 3 is an enlarged fragmentary perspective view of the mounting bar showing the hair spring fastened at its end to the friction adjuster; and

30 Figure 4 is a perspective view of a modified form.

Referring by reference characters to the drawing, numeral 12 is a cup-shaped frame having an apertured stem 11 for the passage 35 of a rotor shaft 10. The rotor shaft is apertured to receive a driving connection with a suitable shaft, preferably a flexible shaft, which latter is to be connected to the rotatable member, the rate of rotation of 40 which is to be measured.

The rotor shaft 10 may have an annular groove 3 to receive a key 5 carried by the stem 11 to prevent axial movement of said shaft 10. The stem 11 may be provided with 45 a recess 21 containing a suitable wick 23 held in position by a cup 25. The purpose of the wick is to carry lubricant for lubricating the engaging surfaces of the stem 11 and shaft 10. An outer casing 27 houses the frame 12

50 and its sleeve 29 is sufficiently extended to re-

tain both the key 5 and the cup 25, as shown in Figure 1. This casing 27 is secured to the frame by a plurality of bolts 31 and nuts 33. The bolts pass through lugs or projections 35 and 37 formed on the frame 12, as 55 shown in Figure 2. There will be a third projection diametrically opposite lug 37. Spacing means 39 on the bolts between the casing 27 and frame 12, together with a washer 41 and an annular fabric washer 43 60 between the casing and the frame serve to secure these parts together in dust-tight relation.

An annular shoulder 45 in the frame supports a C-shaped magnet 13, the magnet having its interpolar gap adjacent bolt 31 in the projection 35. A temperature compensating plate of known characteristics is placed over the magnet poles. This is represented by numeral 46. To hold the magnet in 70 position on shoulder 45 and to also hold the compensator on the poles of the magnet clip 46' is formed with an aperture by which it is dropped over bolt 31 and upon the extension 35. The washer 49 and nut 50 clamp the 75 clip in position, the inner end of the clip firmly engaging the compensator 46.

For the purpose of calibration, a strip of brass or the like 131 may be clamped between parts 46' and 49 and extend substantially radially inward. The inner end of this strip of brass may be provided with a piece of magnetic material 133 being held to the brass strip by fastening means 135. By the provision of this calibrating means, 80 the brass strip may be bent toward or from the plane of the magnet for the purpose of correcting the active magnetic field. Clips 46' on bolts 31 carried by lug 37 and by the diametrically opposite lug are also used. 85 These last-named clips engage the flattened ends 53 of a bridge member 55 which is split as shown in Figure 2. The ends 53 of this bridge rest on the magnet and the clips hold the parts in assembled relation in an obvious 90 manner.

A rotor 9 is secured in any convenient way to the upper end of shaft 10. As illustrated, the end of shaft 10 is reduced to receive on the shoulder so formed the opening within 100

the rotor member 9 and, thereafter, the extreme end of the rotor shaft is crimped to hold the rotor in position. The rotor is formed with a plurality of radial arms 57. Within the opening of the rotor shaft is a carrier 59 having in its lower end an end thrust bearing 61 and near its upper end a hole jewel 63. Secured by threads in the intermediate part of the bridge 55 is a second bearing carrier having a passage therethrough and a hole jewel 65. The openings in the hole jewels 65 and 63 are in alignment and together with the end bearing 61 provide the necessary bearing support for a spindle 67. Secured by fastening means 69 to the spindle 67 is a metallic disc 14 designed to serve as a drag member and to be rotated by the eddy currents against the tension of the hair spring 71 secured to the said spindle and to a rotatable adjusting member. As it is well known in such instruments, the degree of rotation of the drag disc 14 depends upon the rate at which rotor 9 travels, cutting as it travels the magnetic lines of force between the magnet poles.

A regulator arm 73 rests on bridge 55 and is apertured to rotate about the extended end of carrier 65. This regulator arm extends across the bridge and on one side is bent down as at 75 and secured to the lower end of the bent-down portion 75 in a manner to be described is the outer end of spring 71. The other end of the regulator arm is given a double bend and resiliently engages, by its extended end, forked as at 77, the underside of the bridge. Rotation of the regulator arm serves to vary the tension of spring 71.

At the upper end of the spindle is mounted a part 79 carrying an indicating needle 16. The needle moves over a dial plate 19, the peripheral portion of which engages the marginal flanges of casing 27. In practice, there will be a glass cover and a fastening bezel, which parts are conventional and not illustrated.

The invention is more particularly concerned with the attachment of the outer end of hair spring 71. The down-turned end of the regulator arm is, as shown in Figure 3, provided with two slits 91 forming three tongues 93. The outermost of the tongues 93 are provided with bent portions, the direction of the bend being opposite that of a bend in the intermediate tongue 93. As shown best in Figure 3, an arc-shaped tubular member 94 is held between the bent portions of the tongues 93 which are sufficiently resilient to hold the member 94 firmly in position. The curvature of tube 94 corresponds with that of the hair spring. The end of the hair spring is inserted within the tubular member 94. By this means, the end of the hair spring has the same curvature as that of the major portion of the spring. After insertion in the

tube, the spring may be drawn through until the desired tension of the coil is had, after which the tube may be crimped to provide a permanent holding means for the end of the spring. After the spring is firmly secured 70 in the tube, the tube with the end of the spring may be moved relative to the tongues 93, as by slightly pressing the tongues apart. In addition to this provision for adjustment, it will be understood that a fine adjustment may 75 be thereafter made by the rotation of the regulator arm itself about its pivot.

In the use of hair springs in connection with such instruments, it is customary to secure the end of the spring by a tapered pin, 80 after which a fine adjustment is had by manipulating the regulator arm to increase or decrease the tension of the coil spring, this being accomplished by the rotation of the regulator arm on its pivot. In so securing 85 the hair spring by wedging with the tapered pin, the concentricity of the coil at that point is destroyed, because of the flattening effect given to the hair spring at that point, producing a kink therein and more or less affecting the uniformity and efficiency of the coil. By the means described, this disadvantage has been overcome. The hair spring is maintained perfectly concentric up to its very end and including its holding means. 90 The hair spring is therefore not subject to twisting or deformation at its end when fastened.

Figure 4 represents a modified and somewhat simpler form which may be adopted 100 when desired. In this form, the regulator arm is dispensed with and the hair spring supporting arm is formed as an integral part of the supporting bar 97. The downwardly extending arm 98 is suitably split and the 105 outer portions are angularly bent to form depressions 99, cutting down the length of these ends and leaving the center portion straight, its end extending further than the others, this arrangement facilitating the forcing 110 apart of the ends to allow the end of the spring 71 to be pulled through. With this arrangement, any adjustment of the hair spring coil may be quickly and easily made, after which the spring is permanently held 115 in its adjusted position. This modified form employs a minimum number of parts since the conventional regulator arm and tapered pin are both dispensed with. It provides a 120 means of reducing production cost, both in manufacture and assembly.

I claim:

1. In a measuring instrument, a rotary indicating member, a hair spring to restore said 125 indicating member to a predetermined position, a retaining means for said spring holding an end of said spring in substantially concentric relation to the remainder of the spring, said retainings means including an 130

arc shaped tube, the end of the spring received within said tube.

2. In a measuring instrument, a rotary indicating member, a hair spring to restore said indicating member to a predetermined position, a retaining means for said spring holding an end of said spring in substantially concentric relation to the remainder of the spring, said retaining means including an 10 arc-shaped tube, the end of the spring received within said tube, said tube being adjustable circumferentially within the retaining means.

3. In a measuring instrument, an indicating member, a hair spring to restore said indicating member to a predetermined position, retaining means for said hair spring, said retaining means having at least three resilient fingers, the outermost fingers having bent 20 portions, the end of the spring being received and held between said fingers, the intermediate finger having a reverse bend, an arc-shaped tube positioned within the several bends and held by the resiliency of said bent 25 portions, the end of the spring being fixedly secured within said tube.

In testimony whereof I affix my signature.
LOUIS BERG.
